BILL PRINTING AND ADDRESSING MACHINE

Harmon P. Elliott, Watertown, Mass.

Application April 27, 1928, Serial No. 273,364

26 Claims. (Cl. 101—47)

This invention relates to combined stencil-addressing and printing methods and has particular reference to the combined printing of bills or similar matter and to the addressing thereof by the use of stencils.

The bills of some public utility companies and in particular telephone companies, are made up of multiple detachable sections of which one or more sections is presented to the subscriber and the other sections are retained by the company and are used in its various departments. Each section of the bill bears the stencilled address of the subscriber but the printed matter of the sections is usually different.

10 A telephone bill, for instance, may comprise four duplicate sections, two sections going to the subscriber and the other two sections being retained by the telephone company in the different departments thereof.

15 With telephone bills, especially, the subscriber's monthly base rate or exchange service charge may be a part of the stencilled address since this charge remains fixed until the class of service given the subscriber is changed. Toll and other 20 charges are added to the bill after it is printed and addressed and the bill sections have printed data against which such charges are recorded.

25 Heretofore, telephone bills have been printed on separate sheets and have been subsequently addressed in a stencil-addressing machine. This system is not particularly satisfactory because of the difficulty encountered in feeding the blank bills accurately, it being found that the address would fail to register properly with the printed 30 portions of the several sections of the bill. The address might be made to register with the first section of the bill but, due to slippage and other troubles, it might fail to register with following sections of the bill. Furthermore, when the bills 35 are separately printed, mechanism is necessary to pick-off a separate bill from a stack of printed bills and to present the bills to the action of the stencil addressing mechanism. While such pick-off mechanism can be made to operate, its action 40 is not entirely reliable and further necessitates a rather complicated structure.

45 An object of the present invention is a method of making bills, and especially multi-section bills, and the like which consists in addressing the bills and in printing the bills all as integral parts of the bill-making operation, the paper for the bills being taken from a long strip or a roll and the bill being severed from the strip or roll only after it has been printed and addressed.

50 A further object of the invention is a com-

bined stencil addressing and printing machine which operates on a long strip or roll of paper to address and also to print the bill sections, and to sever the completely printed and addressed bill from the strip or roll after the bill has been completely printed and addressed.

A further object of the present invention is the provision of a machine of the type above set forth wherein but one paper feeding means is employed to move the paper into and out of stencil addressing position and also in and out of printing position, thus to insure the necessary accuracy of alinement of or registration between the stencilled address and the printed parts of the bill sections, it having been found difficult to obtain such accuracy of registration if a plurality of paper sheet feeding means were employed. Preferably the sheet feeding means constitutes the bill printing device; and this constitutes a further object of the invention.

20 In a machine of the type set forth, the printing of the bill is effected by an electro-type of roll form which roll as above set forth constitutes the feeding means for the paper sheet. It is another object of the invention to provide the electro-type roll with a continuous periphery that is always in driving engagement with the paper sheet so that the paper sheet is never released while the machine is in operation and thus can not slip and cause the printed matter and address to become misaligned.

25 While the electro-type roll constitutes the means for moving the paper strip through the addressing position and also through the printing position, separate means are provided to pull the paper strip off its roll so that it hangs loose and free for the action of the electro-type roll. The electro-type roll can thus move the paper strip without any particular effort so that there is no tendency for the paper to slip while in the 30 driving engagement of the printing roll and thus cause smudging of the printed matter. This arrangement constitutes a further object of the invention.

35 The stencil addressing section of the machine has a holder in which a pile of superimposed stencils are held in readiness for passage through the addressing position and a stencil receiver into which the stencils are moved after the addresses have been printed. The bill printing roll is located at the end of the addressing section of the machine and in line with the direction 40 of movement of the stencils through the machine and operates to move the paper strip under the stencils when they are in printing position. In 45

the usual stencil machine, the stencil receiver is located below the path of stencil movement so that the stencils can drop into the receiver. Such an arrangement is not practicable with the present type of machine and consequently a further object of this invention is to locate the stencil receiver in elevated position above the path of movement of the stencils so that there is a clear passage for the paper strip to the printing roll and under the stencils.

When the paper strip comes off the roll, it is curved. It is a further object of this invention to provide means to bend the paper strip in a reverse curve, thus to straighten the strip. The straightening means is so arranged that it can bend the paper through a larger or smaller curve thus to compensate for the differences in curvature of the paper strip as the paper roll becomes smaller.

Since the same address is printed on each section of the bill, it is an object of this invention to provide means whereby the bill sheet is moved by successive steps of suitable length and whereby each stencil is used as many times as there are bill sections before the stencil is moved out of printing position and a new stencil is brought into use.

A further object of the invention is generally to improve upon printing and stencil addressing machines and methods.

The bill which is one of the products of the machine embodying this invention is a telephone bill and illustrated in Fig. 1. The bill is printed on a long strip of paper 40 and is severed from the strip after it is completely printed and addressed.

The bill comprises four sections namely a subscriber's bill section *a*, a subscriber's stub section *b*, and two stubs *c* and *d* which are retained by the telephone company. Lines of perforations *e* separate the sections of the bill so that they can be detached readily. After the bill is made up, the subscriber's section *a* and stub *b* are detached from the remaining stubs and are presented to the subscriber. The remaining stubs *c* and *d* are separated for use in separate departments of the telephone company.

The bill has an upper printed section *f* and a lower printed section *g*, the printing of which is carried out by a type printing mechanism which in the present machine is an electro-type roll. The bill has an intermediate section *h* in which the address is located and the base service charge both of which are printed thereon by stencils. Each section of the bill bears a date *k* which is located immediately above the address space. The date is carried by the electro-type roll and is duplicated in the sections of the roll which print the sections *a*, *b*, and *c*. The date *k* is also present in the printed section *f* of the stub *d* and thus is located in the corresponding section of the electro-type roll. The dates are removably connected with the roll so that they can be changed each month or whenever desired.

There is a clear and unobstructed space *l* immediately under the section *f* and above the dates *k* of the sections *a*, *b*, and *c*. This space *l* is continuous throughout the length of the bill or at least is continuous between the bill sections and between the printed matter on the sections and the electro-type roll has a section which bears upon the paper strip in this locality, whereby said

roll is in continuous engagement with the paper.

strip at all times while the machine is in operation so that complete control of the paper strip is assured.

It will be noted that the section *a* of the bill is longer than the remaining sections. Consequently the feeding of the paper strip is varied in accordance with the length of the sections. In accordance with this invention, the addresses for the various sections of the bill are printed as an integral part of the bill making operation; and the addresses are impressed on the paper sheet from stencils before the bill is printed up. This method of making the bill has been found to be highly advantageous in that it provides relatively simple mechanism and secures constant registration between the printed matter and the addresses of the sections.

The stencil printing mechanism of the present machine comprises a bed or table 42 which is supported on standards 44. The stencils are caused to move through a track 46 which is located above and in spaced relation with the table 42 and extends from one end to the other thereof. A stencil holder 48 is located at one end of the stencil track and is adapted to contain a pile of stencils 50 therein which are moved in successive order from the bottom of the pile into the stencil track and into and out of stencil position and thence along the track to a stencil receiver 52 which is located above the track. Printing mechanism is located at an intermediate section of the track and comprises a printing roll 54 carried by a pivoted bifurcated arm 56 that extends beneath the table and is connected by a link 58 to an operating arm 60 which arm is pivoted on a shaft 62 carried by the fixed bracket 64. A platen 66 is disposed beneath the stencil track and the printing roll 54 and is carried at the end of a pivoted arm 68. The reciprocating operating lever 60 has a cam arm 70 that engages a roller 72 of the platen whereby to raise the platen into printing position beneath the stencil and also to move it downwardly out of such printing position. The lever 60 operates both the platen and the printing roll at the same time. The operating lever 60 is connected by a rod 74 to a motor operated power mechanism 76 which receives power through a continuously rotating shaft 78. The power mechanism is common in the art and need not further be described.

The function of the power mechanism is to operate the various parts of the machine, and its operation can be controlled or arrested at will by an operative.

The operating lever 60 also has an arm 79 connected therewith. Said arm has a cam slot 80 which operates a cam follower 82 that is connected with a vertical hub 84, thus to reciprocate said hub angularly. A horizontally extended arm 86 is connected to and reciprocates with said hub and is pivotally connected at its free end with a horizontally extended link 88 that has a longitudinally elongated slot 90 therein provided with an offset section 92 in the free end thereof. A pusher carrier 94 has a pin 96 which is located in said slot. Said pusher carrier is slideable beneath said stencil holder 48 and has a pusher 98 detachably connected therewith which is reciprocated into and out of engagement with the lowermost stencil in the pile to move it out of the pile and into the stencil track. The stencil pusher is operated by the link 88 as it reciprocates and the slot 90 in said rod permits the pusher to be operatively disconnected from the remaining operating mechanism of the address section of the ma-

chine so that the stencils can be held stationary in the stencil track and repeated imprints of the address borne by each stencil can be made on the various sections of each bill. A spring 100 is stretched between the link 88 and the arm 86 and thus tends to maintain the link in such position that the pin 96 is in the lateral extension 92 of the slot, thus to connect the link operatively with the pusher.

Mechanism is provided to hold the link 88 in disconnected relation with the pusher so that the arm 86 and associated mechanism can reciprocate without moving the stencils. The link disabling mechanism includes a multilobed cam 102 which is pivoted on a bracket 104 carried by and located beneath the bed 42. Said cam is also provided with a series of ratchet teeth 106 and a disc having a series of notches 108 which are located in line with the ratchet teeth. A leaf spring 110 fits releasably into any one of said notches 108, thus to hold the cam against unintentional movement. An arm 112 is pivoted concentrically with the cam and is connected with said reciprocating arm 86 by a link 114. Said arm carries a spring pressed pivoted pawl 116 which is arranged to engage the ratchet teeth 106. Thus each reciprocatory movement of said arm 86 serves to advance the cam by the extent of one tooth. An arm 118 is pivoted to said bracket 104 and carries two rolls of which the roll 120 engages the link 88 and the roll 122 engages the cam 102. Thus, when the roller 122 falls into one of the notches 124 between the lobes of the cam, the spring 100 causes the arm 88 to move into operative engagement with the pusher so that the pusher can be reciprocated. The peripheral extent of the notches 124 is such that one reciprocatory movement of the arm 86 brings the roller 122 out of the notch and onto a lobe of the cam, thus to disconnect the pusher from its reciprocating mechanism. The peripheral extent of the lobes of the cam between the notches thereof is such that the arm 86 can make three complete reciprocatory movements without a change of stencils. Each stencil is thus caused to make four impressions on the bill strip.

The printing roller 54 receives ink in a more or less common manner from the ink roll 126. Ink is supplied to said roll by any suitable or usual mechanism 128 which need not be further described.

Since the stencil receiver 52 is located above the stencil tracks, means are provided to raise the stencils from the tracks and deliver them successively to the bottom of the pile of stencils in the stencil receiver. Said means is constructed essentially as illustrated in the Sterling Elliott Patent No. 1,210,440, dated January 2, 1917. It comprises essentially a casing 130 into the bottom of which the stencils are delivered from the stencil track, see Figs. 4, 30, and 31. The side walls of the casing have opposed circular grooves 132 in which the opposite ends of the stencils are located. A shaft 134 is journaled in the casing and carries a hub 136 to which is pivoted a pair of spring pressed arms 138. Said arms lie close to the opposite end walls of the casing and overlie the stencil grooves therein. When the shaft 134 rotates, said arms are carried around with it and move the stencil upwardly in said circular grooves and into the teeth of a pair of opposed worms 140 which are located at the top of the casing opposite the grooves 132 therein and immediately under the stencil receiver. Said worms are driven by gears 142 from the shaft 134 and serve to ele-

vate the raised stencil above the circular grooves 132 and into the receiver. The top faces of the worms form supports for the pile of stencils in the holder. While this particular apparatus is not 5 novel, per se, its combination with the other operative components of the machine, so that the billing strip can pass under the stencil receiver to the printing mechanism hereinafter to be described, is considered novel.

10 The bill printing and associated mechanism is carried by the table 42 immediately in the rear, or at the left, Fig. 3, of the stencil receiver 52. The printing mechanism includes an electro-type roll which prints and also drives the paper sheet, 15 mechanism for inking the electro-type roll, and mechanism for perforating the bill between the sections and for severing the completed bill from the strip.

20 The power for operating these mechanisms is obtained from the power mechanism 76. A shaft 144 is journalled in suitable brackets at the rear of the table 42 and is driven from the shaft 78 of the power mechanism by a belt 146. Said shaft 144 serves to drive the inking mechanisms for 25 both the stencil addressing mechanism and the bill printing mechanism. A second power-actuated shaft 148 is located beneath the table 42 and is positively driven from the shaft 78 by a chain 150 and speed reducing gearing 152. Said shaft 30 148 thus has a positive driving connection with the shaft 78 so that the printing mechanism can operate in timed relation with the stencil operating mechanism.

35 A counter shaft 154 is supported in bearings above and at the rear of the table 42 and has a large gear 156 thereon which is driven from the main shaft 148 by a small gear 158 thereon and an interposed idler gear 160, see especially Figs. 4 and 10. Said countershaft serves to operate the 40 bill printing, perforating and severing mechanisms. The shaft 134 of the stencil elevating mechanism is driven from the main shaft 148 by sprockets and a chain 162 so that the stencil elevating mechanism operates in timed relation with 45 the other components of the machine.

50 The bill printing mechanism includes an electro-type roll 164 which is loose on a shaft 166 journalled in opposed standards 168 and 170 rising above the table 42 and located on opposite sides of the line of movement of the bill sheet. The printing roll is illustrated specifically in Figs. 10, 19, 20, and 21. The electro-type roll comprises a hub 172 which is loose on said shaft 166 and has a drum composed of four sections, three 55 of the sections 177 being of the same peripheral extent and corresponding to the bill sections *b*, *c*, and *d*, Fig. 1, and the fourth section 178 of greater length and corresponding to the length of the bill section *a*. The periphery of the drum is provided with a raised continuous ledge 180 which is located on the periphery to register with the blank section *l* of the bill and constitutes a driving face 60 of the roll which is continuous between the bill sections so that the roll is always maintained in driving engagement with the bill strip. The drum is provided with a dove-tailed channel 182 at the left of the ledge 180 and occupies the space corresponding with the section *f* of the bill. The electro-types are adapted to be retained in said 65 groove to print the sections *f* of the bill sections. The electro-types are retained removably in place by undercut segments 184 which are removably connected with the drum, or the sections thereof. The drum is also provided with dove-tailed 70 grooves 186 in its sections in which type is adapted

75 to be inserted to print the dates *k* of the bill. This type can be removed and changed each month or whenever desired. The drum is also provided with another dove-tailed groove 188 which corresponds to the section *g* of the bill and is adapted to receive electro-types for printing this part of the bill. The electro-types are held in place by segments 190 which are secured to the end of the drum sections by screws 192. The drum is adapted to be rotated intermittently in 10 one direction.

80 Brake mechanism is provided to hold the drum against movement when the driving force thereon is removed. The brake mechanism includes a 15 brake drum 194 which is integral with the hub 172 and is located at one end thereof and adjacent the bearing standard 168. A pair of brake shoes 196 encircle said drum and have brake linings 198 that bear thereagainst. Said brake shoes are pivotally mounted on a screw 200, Fig. 20 10, carried by the standard 168 or an extension thereof and have depending lugs 202 at the lower ends between which a spring 204 is stretched, whereby to maintain the brake shoes in constant frictional engagement with the brake drum. Additional pressure applying means is provided 25 which comprises arms 206 bearing at their one ends against intermediate portions of the brake shoes and at their other ends against the side faces of the standard 168. Screws 208 are passed 30 loosely through said arms 206 and are screw threaded into said standard and have compression springs 210 which encircle the screws and bear against said arms thus urging them inward and against the brake shoes.

35 The printing or electro-type roll is driven intermittently by steps the lengths of which correspond with the peripheral extent of the roll and bill sections. To this end, the hub 172 is provided with a ratchet wheel 212 which has ratchet teeth 214 on the periphery thereof, which teeth are so located with respect to the ends of the electro-type sections that each section is rotated into and out of engagement with the bill strip during each step movement of the roll. The 40 spacing between the teeth 214 corresponds with the peripheral extensions of the electro-type section. Thus the spacing between two of the teeth is longer than between the other teeth, the increased length being proportional to the increased 45 length of the section 178 over the other sections.

50 The roll is driven by an arm 216 which is fixed to the shaft 166 and reciprocates with said shaft. A pawl 218 is pivoted to said arm and has a projection 220 that is constantly urged for driving 55 engagement with the ratchet teeth by a tension spring 222. The stroke of said arm 216 is adapted to be sufficient to move it throughout the greatest space between the teeth and engage the teeth successively. The shorter spacing between the teeth is adapted to be such that the arm or the pawl thereof can not move the ratchet wheel more than the distance between the successive teeth at each stroke.

60 The shaft 166 is reciprocated by means of a gear 224 which is fixed to said shaft and engages a rack 226 which is vertically slidable in a guideway 228, Fig. 4, of the standard 170 and a registering guideway in the table 42. The rack is reciprocated, see Fig. 10, by a connecting rod 230 65 that is pivoted at its upper end to the middle of the rack and at its lower end to a crank arm 232 fixed to the end of the driving shaft 148. Thus, as said driving shaft continuously revolves, said shaft 166 is given a reciprocatory movement which 70

through the ratchet wheel 212 and arm 216 results in an intermittent movement of the printing roll in one direction.

- Ink is supplied to the electro-type or printing roll 164 by an inking mechanism which includes a spreading roll 234 fixed to a shaft 236 journalled in opposed brackets 238 carried by the standards 168, 170. A second shaft 240 is journalled in said standards below said transfer roll.
- 10 A bracket having opposed arms 242, Figs. 3 and 16, is journalled on said shaft and carries inking mechanism indicated generally at 246 for supplying said spreading roll with ink. A spring 248 serves to urge said frame towards the spreading roll to maintain the inking mechanism carried by said frame in engagement with said roll. A pair of inking rollers 250 and 252 are provided to transfer ink from the spreading roll to the electro-type roll. The ink roll 250 is journalled 20 on a shaft carried by arms 254 which are fixed to the shaft 240. The ink roll 252 is carried by a frame 256, see Figs. 17 and 18, having outstanding arms 258 which carry a shaft that supports the roll 252. The rolls 250 and 252 are thus on 25 opposite sides of the shaft 240.

The inking mechanism is driven continuously from the shaft 144 by a belt 247 which connects said shaft with a shaft 249 of the inking mechanism.

- 30 It has been found that if the ink rolls were in continuous engagement with the intermittently movable electro-type roll, they would leave a heavy line of ink on the electro-type roll when it was stationary. Consequently means are provided by which the inking rolls are in contact with the electro-type roll only when said electro-type roll is moving and are out of contact with said electro-type roll and are in contact with the spreading roll 234 when the electro-type roll 40 is stationary. Said means includes an arm 260 which is fixed to the shaft 240 and thus can raise and lower the roll 250. A second and opposed arm 262 is fixed to a tube 264 that encircles the shaft 240 and is fixed to the frame 45 256 that carries the other ink roll 252 so that said arm 262 can raise and lower the roll 252. Said opposed arms are provided with screws or pins 266 that operate in vertically elongated slots 268 and the upper horizontal extensions 268a 50 thereof are formed in a pair of vertical levers 270 that are provided at their upper ends with finger extensions 272. Said arms are normally urged apart by a compression spring 274 carried by and located between said levers, see Fig. 14. 55 The lower ends of said levers are independently pivoted to oppositely outstanding arms 276, see Figs. 14 and 19, that are loose on the shaft 166 that supports the electro-type roll.

- Cam rollers are carried by said arms 276 and 60 are disposed above and are adapted to be engaged by the four teeth 280 of separate star wheels 282 that are carried by the counter shaft 154, see Figs. 14, 10 and 4. The spring 274 bears on said levers 270 and thus serves to maintain 65 the pins 266 associated with the inking rolls in the slot-extensions 268a, thus to maintain the levers in operative engagement with the ink rolls. Consequently, as said arms 276 are raised and lowered by the teeth 280 of the star wheels, the 70 rolls will be alternately lowered to engage the electro-type roll and be moved out of contact with said roll and into engagement with the continuously rotating ink spreading roll 234. The position of the star wheels on the counter shaft 75 154 is such that the ink rolls are moved down-

wardly into engagement with the electro-type roll as it starts to rotate and is moved away from engagement with said roll when it stops. The spacing between the teeth of said star wheel corresponds with the varying lengths of the sections of the electro-type roll.

The ink rolls 250 and 252 are provided with aligned continuous peripheral grooves 251 and 253 respectively which are located in the rolls to register with the latch 180 of the printing roll so 10 that the driving face of the ledge is maintained free from ink.

It is desirable sometimes to permit the operative to hold the ink roll out of engagement with the electro-type roll as, for instance, when the operative finds that the electro-type roll is becoming too heavily inked. This can be done by pressing the levers 270 inwardly toward each other by engagement of the finger extensions 272. This movement will cause the pins 266 associated 20 with said ink rolls to occupy the elongated slots 268 in said levers. The lengths of said slots are greater than the throw of said levers. Consequently, the rolls will be held in operated position by their springs 284 regardless of the vertical reciprocal movement of said levers.

It is also desirable to hold said ink rolls out of engagement with both the electro-type roll and the ink spreading roll as, for instance, when the machine is not in use or adjustments are 30 made thereto. To this end, a cam member 286, Figs. 10 and 13, is located over the supporting arms for the ink rolls and at one side of the ink spreading roll. Said cam member is loosely connected with the shaft 236 of the spreading roll, 35 which shaft passes through a vertically elongated slot 288 of the cam member. The cam member has a bushing 290 which is rotatable therein and is eccentrically connected with a shaft 292 that is journalled in one of the standards 238 and has an operating handle 294 fixed to its outer end. Thus, by reciprocating said handle, the cam member can be moved to the right and to the left. The cam member has a cam face 296 at its lower end which overlies one 40 of the supporting arms 258 of the ink roller 252. The cam face also has a projection 298 which overlies and is adapted to engage one of the supporting arms 254 of the ink roller 250. Thus, when said cam member is urged toward the left, 45 Fig. 13, the projection 298 is caused to engage the arm 254 and lower the ink roll 250 from engagement with the spreading roll. The same movement serves to tilt the cam member 286 and cause the cam face 296 thereof to press against the arm 258 of the other ink roll, thus also to lower it from engagement with the spreading roll. The cam member is held releasably in 50 either one of its positions by a spring pressed pin 300, see Figs. 10 and 3, carried by a bracket 55 299 adapted to seat in either one of two recesses in the handle 294.

An impression cylinder, platen, or make-up roll 302 is disposed beneath the electro-type roll 164 and operates through an opening in the table 42 and cooperates with the electro-type roll to support the bill strip as the electro-type roll prints thereon. Said impression roll, see especially Figs. 10 and 22 through 27, comprises a drum 304 that is composed of two connected 65 sections rotatable on a shaft 306 that is journalled in brackets 308, carried by and depending beneath the table 42. The shaft 306 is provided with eccentric sections 310 and 312 that are journalled in said brackets 308 so that when 70 75

said shaft is reciprocated by the handle 314 the impression roll can be raised and lowered into and out of cooperative relation with the electro-type roll. A spring urged latch 316, see Fig. 3, is 5 in normal engagement with a notch in the eccentric section 310 of said shaft for the purpose of holding said impression roll releasably in operative position.

The periphery of the impression roll is covered with several superimposed layers of paper strips 318, Figs. 26 and 27, the ends of which are located in an axially extended peripheral slot 320 of the make-up roll. A strip retaining bar 322 is located removably in a groove 324 of 15 said roll at said slot and has projections 326 which extend into said slot and into perforations 328 at one end of the paper strips. The other end of the paper strip is provided with notches 330 in which said projections are received. The 20 ends of the paper strips are clamped to each other and to the impression roll by a bar 332 which is integral with an arm 334 carried by a shaft 336 journaled in the end walls of the roll. An arm 338 is fixed to said shaft externally of the 25 impression roll and in a recess in the end wall thereof and has a pressure screw 340 that bears against the wall of the recess and thus clamps the bar 332 against the ends of the paper strips. One of the intermediate paper strips may have 30 patches 342, Fig. 27, applied in the usual manner to increase the printing pressure between selected parts of the electro-type roll and the bill strip whereby to obtain a uniform imprint of type that might otherwise be printed faintly.

35 The impression roll is driven by the electro-type roll and to this end the electro-type roll has a gear 344 fixed thereto which meshes with a similar gear 346 fixed to the electro-type. The teeth of both rolls are sufficiently long to permit 40 the make-up roll to move downwardly out of pressure applying relation with the electro-type roll while maintaining the driving connection between the rolls.

The paper for printing the bills is contained 45 in a large roll 40a, Fig. 3, and is drawn from said roll by feeding mechanism which is adapted to remove the paper at a rate which is slightly in excess of the rate of movement of the paper by the electro-type roll. The feeding mechanism 50 is illustrated in Figs. 3, 28 and 29.

The feeding mechanism is located beneath and is carried by the table 42 under the stencil receiver 52 and includes a driving roller 348 fixed to a shaft 350 which is journaled in brackets 55 352 carried by the table 42. The driving roll has end flanges 354 which retain the paper strip against movement axially of the roller. The roll is driven by bevel gears 356 from the main driving shaft 148. A pressure roller 358 is located 60 above said driving roll and is normally urged toward said roll whereby to hold the paper strip in engagement with the driving roll. Said pressure roll is journaled on a shaft 360 carried by arms 362 fixed to a shaft 364 journaled in the 65 brackets 352. A spring 366 is connected between one of said brackets and one of said arms whereby to urge said pressure roll toward the driving roll. Said pressure roll can be moved upwardly out of cooperative relation with the pressure roll by 70 a handle 368 which is fixed to said shaft 364. A guide roll 370 is journaled on said shaft 364 and serves to wrap the paper strip partially about the driving roll.

The paper strip is adapted to feed into a loop 75 40b which hangs free, and the electro-type roll

is adapted to draw the paper strip from the loop. The paper strip thus is free to move under the electro-type roll without the necessity for rotating the paper roll 40a.

The paper feeding mechanism is adapted to withdraw the paper strip from the paper roll 40a at a rate which is slightly greater than the rate of movement of the paper strip under the action of the electro-type roll. Consequently, the paper loop 40b tends to increase in length so that 10 the operative is required to watch the paper loop and to disable the feeding mechanism momentarily, by manipulation of the handle 368, when the paper loop becomes too long or drags on the floor, thus to enable the electro-type roll to take 15 up the excess amount of paper before the feeding mechanism is again put into operation.

The paper strip passes from the loop over a guide roll 371, Fig. 3, and thence toward the right immediately above the table and under the stencil tracks 46. At the right of the stencil printing mechanism, the paper strip is wrapped over a cylindrical bar 372 located above the table under the stencil tracks, and has its direction of movement reversed. The bar 372 is fixed in slot- 25 brackets 374 through the slots of which clamping screws 376 are passed, see Figs. 4, 8 and 9, whereby to secure the bar in adjusted position beneath the stencil track. The brackets 374 also act as guides to prevent sidewise move- 30 ment of the bill strip. The strip in passing over the bar 372 is deflected downwardly and immediately over its bottom pass by a bar 378 fixed in the ends of arms 380 that have longitudinally elongated slots 382 therein through which clamp- 35 ing screws 384 are passed and are screw threaded into the brackets 374. As thus arranged the bar 378 can be moved toward and also away from the bar 372.

Said bars constitute a tension mechanism 40 which serves to keep the paper taut under the stencil during the addressing operation. Said bars also constitute mechanism to remove the curl from the paper strip since they act to flex the paper strip in a direction which is opposite 45 to the direction of the curl of the strip. As the roller 40a becomes smaller the curl in the paper strip becomes greater. The bar 378 is adapted to be moved closer to the fixed bar 372 thereby to increase the bend of the paper in the opposite direction and compensate for the increased curve 50 of the strip.

The bill strip immediately and prior to passing into the bite of the electro-type and impression rolls is caused to receive transverse lines of perforations e, Fig. 1, between the bill sections. The perforating mechanism, see Figs. 3, 4 and 12, includes a bar 386 which is carried by the table 42 and has a horizontal slot 388 therein through which the paper strip is threaded. Said bar is 60 also provided with a vertical slot therein into and out of which a toothed perforating plate 390 can reciprocate into and out of contact with the paper strip when it is stationary. Said plate 390 is fixed to a reciprocatory arm 392 that is pivoted 65 on a shaft 394 that is constantly urged for movement in a clockwise direction by a tensile spring 396 carried by an extension 398 of said arm. Said arm is released for reciprocatory movement by a disc 400 fixed to and driven by the counter-shaft 154. The arm 392 has a roller 402 which is adapted to pass into the successive notches 404 formed in the periphery of said disc, thus to permit the spring 396 to move the toothed plate 390 into contact with the paper strip. Three notches 70

404 are here shown which permit making the three lines of perforations between the short sections of the bill. The bill is not perforated at the end thereof where it is to be severed from 5 the strip, and consequently the peripheral spacing between two of the notches 404 is greater than between other notches.

The bill strip has a tendency to adhere to the electro-type roll by reason of the ink thereon.

- 10 Consequently mechanism is provided to detach the printed paper strip from its adherency with said roll. Said mechanism, see Figs. 3, 4, and 15, comprises a bracket 406 which is supported in elevated position above the table 42 at the discharge 15 of the electro-type roll and above the path of movement of the bill strip. A supporting member 408 is disposed beneath said bracket and is pivoted thereto at 410 and has springs 412 which urge it in a clockwise direction in Fig. 3. Said supporting 20 member has a pair of opposed arms 414 in which a shaft 416 is axially movable. Rollers 418 are journaled on said shaft and engage with the top or printed face of the bill strip. The shaft and its roller are adjustable laterally so that the rollers 25 can engage unprinted sections of the bill strip. The completely printed and addressed bill passes from the electro-type roll and under the stripping mechanism to a severing mechanism which is shown in Figs. 3, 4 and 11. The severing mechanism includes a bracket 420 fixed to the end of the table 42 in line with the path of movement of the bill strip and has a knife blade 422 attached thereto. A reciprocable severing knife 424 cooperates with said knife blade and is pivoted to 30 said bracket 420 by a screw 426. Said blade is biased for shearing movement by a tensile spring 428 connected to said bar 420 and to a fixed support 430. The cutting movement of said blade 424, under action of said spring 428, is governed by a disc 432, fixed to the countershaft 154. Said disc has a notch 434 therein into which a roller 436 carried by the blade 424 is adapted to fall whereby to permit the spring 428 to operate the knife blade and shear off the completed bill. The 35 side walls of the notch in the disc serve to elevate the blade into its inoperative position shown in Fig. 11. A pressure member 438 bears yieldingly upon the paper strip in front of the severing knife or shears to hold the paper strip down upon the 40 table as the knife 424 is raised upwardly. The separate completely printed and addressed bills fall into an inclined tray 440 from which they can be removed from time to time.

The operation of the parts is essentially as follows: Paper is withdrawn from the roll 40a in a continuous manner and forms into the loop 40b. The electro-type roll withdraws the paper from the loop in an intermittent or step by step manner. While the paper is stationary, the addressing 45 mechanism operates to print the address on the paper strip. Four addresses are here printed before the stencil is moved out of printing position and a new stencil is brought into action. During three stationary periods of the paper strip, the perforating mechanism operates to perforate the paper strip between the bill sections. During the next following stationary period, the perforating mechanism is idle. At this period, the severing mechanism severs the completely printed 50 bill from the paper strip. If, however, the severing knife was at a greater or less distance from the electro-type roll, it might operate at the same time the perforating mechanism operated. At each movement of the electro-type roll, one of the 55 bill sections is printed.

I claim:

1. A bill addressing and printing machine having addressing mechanism and printing mechanism from one to the other of which mechanisms a bill sheet is adapted to be moved in the order named, said addressing mechanism having means to print the same address a determined number of times and thereupon to select a different address for addressing the succeeding bill sheet, operating means for said mechanisms arranged to effect the addressing of the sheet when the sheet is at the addressing mechanism and to effect the subsequent printing of the sheet when the sheet is subsequently at the printing mechanism, and sheet advancing mechanism arranged to advance 10 a bill sheet through the addressing mechanism and through the printing mechanism at the same rate of movement. 15

2. A machine for printing and addressing multi-section bills having reciprocating stencil addressing mechanism, perforating mechanism, rotary printing mechanism, and severing mechanism, all arranged in line in the order named, said perforating and severing mechanisms being independent of the printing and addressing elements of said printing and addressing mechanisms, and operating means for said mechanisms effective to present a bill section of a paper sheet successively at the same rate of movement to the 20 action of said mechanisms in the aforesaid order. 25

3. A machine for printing and addressing multi-section bills having a reciprocating stencil addressing mechanism and a rotary printing mechanism, operating means for said mechanisms including means effective to move a bill section of 30 a paper sheet to the action of said mechanisms in succession and out of the reciprocating addressing mechanism and into the rotary printing mechanism at the same rate of speed, said printing mechanism having printing means to print the body of the sections of the bill and said stencil mechanism having stencil feeding means and means to apply the address of a single stencil successively to the paper sheet in successive localities wherein the addresses will register with the 35 printed bodies of all of the sections and thence to replace the stencil with a different stencil. 40

4. A machine for printing and addressing multi-section bills having reciprocating stencil addressing mechanism, rotary printing mechanism, 50 operating means for both the aforesaid mechanisms including means effective to hold a sheet taut between said mechanisms and to move successive sections of the taut sheet in succession to the actions of said mechanisms, said stencil addressing mechanism having means to effect the repeated impression of the same stencil in different localities on the paper sheet and thereafter to replace the stencil by a different stencil, and said printing mechanism having means to print the body of the bill in sections which are in register with the series of the same address on the sheet. 55

5. A machine for printing and addressing multi-section bills having a stencil addressing mechanism and printing mechanism from the action of one to the other of which a paper sheet is adapted to be moved in succession, said stencil addressing mechanism having means to move successive stencils into and out of addressing position, addressing means operable on the stencils when they are in addressing position to apply the addresses thereon to the paper sheet, means to effect the repeated operation of said addressing means on each stencil while it is in printing 60 65 70 75

position, the paper sheet being moved subsequent each addressing operation so that the same address is repeated in different sections on the paper sheet, said printing mechanism having means to print the body of the sections of the bill in localities which are in register with the successive addresses on the sheet, and means to hold the sheet taut from one mechanism to the other and to advance the taut sheet.

10. 6. A printing and addressing machine comprising stencil addressing mechanism including means to move a plurality of stencils in successive order into and out of addressing position and to effect a plurality of addressing operations upon each stencil when it is in addressing position, and type printing mechanism, said type printing mechanism and said stencil addressing mechanism arranged to operate on a paper sheet which is moved in succession between said mechanisms, 15 and said type printing mechanism having means which moves the successive sections of the paper sheet intermittently both into and out of the action of said stencil addressing mechanism and into and out of type-printing position at the same 20 rate of movement.

7. In an addressing machine, the combination of addressing mechanism, means to move successive sections of a paper sheet in a step by step manner into and out of the action of said addressing mechanism, means to present a loop of paper to the action of said paper moving means, and means to feed paper to said loop in a continuous manner, said paper moving means also constituting printing mechanism which prints 35 upon the sheet.

8. In an addressing machine, the combination of addressing mechanism having elements which reciprocate into and out of engagement with a paper sheet, normally continuously operated means to deliver a long sheet of paper in loop form, and intermittently operated means to withdraw the paper sheet from the loop and move it through the action of said addressing mechanism, said paper moving means also constituting printing means which prints upon the paper sheet.

9. A printing and stencil addressing machine having stencil addressing mechanism and printing mechanism between which a paper sheet is 50 adapted to be moved in succession, said printing mechanism including a printing roll which constitutes means to move the paper sheet through the action of said addressing mechanism, and said printing roll having a sheet engaging face which 55 has a continuous peripheral engagement with the sheet, and means which positively holds said roll stationary at definite positions thereof.

10. In a strip-bill printing and multiple-addressing machine having one mechanism for 60 printing a set of unchanging legends distributed over separate sectional areas arranged lengthwise of such strip, and another mechanism for printing a single name and address once on each of a plurality of sections of any one strip 65 bill, and other names and addresses on corresponding sections of successive strip bills, the combination with said above recited apparatus, of a single device adapted to feed said strip by steps of unequal length through one 70 of said printing mechanisms and to locate the beginning of the strip bill in the address printing mechanism in predetermined register with the beginning of an address and the beginning of the strip bill in legend printing mechanism in 75 predetermined register with the beginning of the

legend; whereby uniform registration in all bills between said unchanging legends and said changing names and addresses is assured and any slight initial error in such registration is non-cumulative throughout an unlimited number of operations, said legend printing mechanism comprising a rotary type cylinder, and said feeding device comprising gripping means operated by said cylinder, and a pawl and ratchet wheel mechanism arranged to give unequal intermittent partial rotation to said cylinder.

11. In a strip-bill printing and multiple-addressing machine having mechanism for printing a standardized set of legends distributed over separate sectional areas arranged lengthwise of such strip, means for printing a single but variable name and address once on each of a plurality of sections of such strip, and a device for intermittently feeding said strip by steps of different amounts through said name-printing means, the combination with said above recited apparatus, of means for positively holding said strip against advance from successive predetermined positions with reference to said name printing means throughout each period between successive operations of said feeding device, whereby there is ensured accurate registration of the name and address with the other printed matter on each bill section, said mechanism for printing said standardized legends comprising a 20 revolute type-bearing cylinder, and said strip feeding device comprising an annular, full faced section on said cylinder.

12. In a strip-bill printing and multiple-addressing machine having mechanism for printing a standardized set of legends distributed over separate sectional areas arranged lengthwise of such strip, means for printing a single but variable name and address once on each of a plurality of sections of such strip, and a device for intermittently feeding said strip by steps of different amounts through said name-printing means, the combination with said above recited apparatus, of means for positively holding said strip against advance from successive predetermined positions with reference to said name printing means throughout each period between successive operations of said feeding device, whereby there is ensured accurate registration of the name and address with the other printed matter on each bill section, said mechanism for printing said standardized legends comprising a 40 revolute type-bearing cylinder, and said strip feeding device comprising an annular, full faced section on said type-bearing cylinder cooperating therewith, and said strip feeding device and said strip holding means comprising an annular, full faced section on said type-bearing cylinder free from type forming depressions, together with apparatus 45 adapted to give said cylinders intermittent partial rotations.

13. In an apparatus for printing and addressing a series of multisectio bills for public service corporations, and the like purposes, which said apparatus comprises a rotary printing mechanism adapted to print repetitions of an unchanging set of legends distributed over separate sectional areas of a strip of paper which are arranged in line one with another, and reciprocating platen mechanism adapted to print a succession of names and addresses, each one of said names being repeated upon each of several sections of each particular bill only, the combination with said above recited apparatus of means arranged to move said bill strip along a continuously uniform straight path between said mechanisms 65 70 75 80 85 90 95 100

5 by steps of different lengths which position the successive sections of a bill successively in addressing position each time said platen addressing mechanism is operated to print the same address and the first section of a different bill at the beginning of printing a different address.

14. In an apparatus for printing and addressing a series of multisection bills for public service corporations, and the like purposes, which said 10 apparatus comprises a rotary printing mechanism adapted to print repetitions of an unchanging set of legends distributed over separate sectional areas of a strip of paper which are arranged in line one with another, and reciprocating platen 15 mechanism adapted to print a succession of names and addresses, each one of said names being repeated upon each of several sections of each particular bill only, the combination, with said above recited apparatus, of means adapted 20 to move said bill strip along a straight path between said printing mechanisms together with a positive stop device associated with said strip moving means adapted to cause said strip to come to rest, before each name printing operation 25 with its section on which the name is then to be printed at a predetermined, exact distance from said legend printing mechanism, whereby there is ensured accurate registration between each printed name and the portion of the legend 30 to be associated therewith on each section of the completed printed bill.

15. A combination such as defined in claim 14 in which roller sections rigidly connected to said 35 rotary printing mechanism form part of said strip moving means, and a pawl and ratchet wheel device and stop therefor form part of said strip moving and stop mechanism.

16. A multi-section bill printing and addressing apparatus comprising, in combination, a rotary web-printing press comprising web feeding 40 means adapted to print repetitions of an unchanging legend, one on each bill length of such web, mechanism for giving said rotary press a series of intermittent partial rotations each 45 adapted to print one section of said bill with intervening periods of rest, an intermittently operating platen press located on the intake side of said rotary press and adapted to operate on the web of paper before it is drawn into said 50 rotary press, gearing connecting the two presses timed to cause said platen press to grip said web only while the rotary press is at rest, a track for stencils passing through said platen press, a magazine for stencils at one end of said 55 track, a plurality of stencils stacked therein, and means for feeding them one at a time along said track to said platen press during the periods of movements of said web, said feeding means being adapted to operate only once for each 60 complete revolution of said rotary press; whereby, each of a series of names and addresses is stencilled upon each of the sections of a bill length of said web, and said bill length then fed to the rotary press and the unchanging legend 65 printed thereon in registry with said names and addresses.

17. In a printing machine having means for printing a plurality of repetitions of periodically changing data on a strip, and means for printing unchanging data on the strip, and, in combination therewith, a single feeding device for advancing a taut strip intermittently by steps of predetermined and different lengths through said changing-data printing means and positioning 70 the strip in said unchanging-data printing means 75

with the changeable data thereon in register with the unchanging-data printing means so that said changing and unchanging data is printed on the strip in predetermined and unchanging relation with each other.

18. In a printing machine, the combination of means having a continuous uninterrupted driving engagement with a bill strip for feeding it through the machine, means for printing a plurality of repetitions of periodically changing data 10 at predetermined and successively different intervals on the bill strip, and means for printing an unchanging impression in predetermined and unchanging relation with said periodically-changing data, and means for operating said bill 15 strip feeding means to advance the bill strip intermittently successively different distances through said changing data printing means between operations thereof.

19. In a printing machine, the combination of means having a continuous uninterrupted driving engagement with a web for feeding it through the machine, means for intermittently driving said means by successively variable and unchanging amounts, means for printing a plurality of repetitions of periodically changing data at predetermined and successively different intervals on the web, and means for printing an unchanging impression in predetermined and unchanging relation with said periodically changing data. 20

20. In a printing machine, means for feeding successive long and short unchanging lengths of a web through the machine including feed rolls having a continuous and uninterrupted driving engagement with the web, driving means for at least one of said rolls having an intermittent driving connection therewith of successively variable extent, means for printing a plurality of repetitions of periodically changing data on said long and short unchanging lengths, and means 35 for printing unchanging data on said unchanging lengths in predetermined and unchanging relation with said changing data. 40

21. In a printing machine, means for printing a plurality of repetitions of periodically changing data at predetermined and successively variable intervals on a bill sheet, type means for printing unchanging data at predetermined and successively variable intervals on the sheet, and means for effecting the constant and unchanging registration of the periodically changing data and unchanging data on the sheet including a single pair of sheet-feeding rolls which advance through the action of both aforesaid means by successive long and short lengths, each of which 50 is unchanging. 55

22. An addressing machine having means to feed a bill through the machine including a bill advancing device having a bill driving face, means which prints unchanging data at a plurality of locations along the length of the bill, means which prints address data at a plurality of locations along the length of the bill, means providing a plurality of successively operable bill positioning members for defining the stationary locations of the bill, said successive positioning members being successively spaced apart along said bill driving face by distances corresponding to the distances between successive address data locations, at least one of said positioning members having a predetermined relation with respect to a predetermined part of said data printing means, and means which brings said positioning members successively into play and which in combination with said positioning members 60 65 70 75

effect the positive registration of the unchanging and changing data on each bill and on all successive bills.

23. A machine for printing and addressing a series of bills having different addresses and common printed matter with the printed data and the addresses on each bill having constant registration to each other and with each bill having repetitions of the same address thereon, comprising addressing mechanism having means for applying a succession of groups of different addresses, each group consisting of repetitions of the same address, printing mechanism including a printing device for applying repetitions of the same data, and means for effecting the application of the addresses and data on successive bill blanks in such manner that an error in registration between the address and the data or any bill blank is not cumulative in the successive bill blanks, said means comprising means for intermittently advancing the successive bill blanks by steps of different length while lying flat between said addressing and printing mechanisms, bill-blank positioning means including means for stopping each bill blank successively with the part on which the printed matter is to be printed in the same predetermined positions, means for operating said addressing mechanism to apply the address to successive portions of the blank bills when the bill blank is stationary in such successive positions, said positioning means including means for starting the feeding of the bill blank to be printed with the part on which the printed matter is to be printed in exact invariable predetermined relation to said printing device, and means for operating said printing mechanism to print the printed matter on the bill blank in exact predetermined relation to the addresses thereon, whereby the possibility of cumulative error in the relation of the printed matter to the addresses in successive bills is avoided.

24. A bill addressing and printing machine having addressing mechanism and printing mechanism from one to the other of which mechanisms a bill strip is adapted to be moved, said addressing mechanism having means for presenting a plurality of address bearing plates successively in the same addressing position, means to print the same address a predetermined number of times and thereupon to select a different address plate for addressing a succeeding bill strip, said printing mechanism having type characters located at a printing position for printing a set of unchanging legends distributed over separate sectional areas of said strip and for repeating said set of legends on successive strips, and a strip advancing device including a strip driving member having a strip driving face that moves in the direction of advance of the sheet, a plurality of successively operable strip-positioning members distributed lengthwise of

said face and successively spaced apart by distances corresponding to the distances between successive addresses, which device advances the strip bill intermittently by steps of different length corresponding to the spacing between successive positioning members through the address position and locates the beginning of the strip bill in the addressing position in predetermined register with the beginning of the address on an address plate, and the beginning of the strip bill in the printing position in predetermined register with the beginning of the set of legends provided by said type characters, whereby the possibility of cumulative error in the relation of the printed matter to the addresses in successive bills is avoided.

25. In a printing machine for printing a series of bills wherein each bill has spaced repetitions of the same address and printed data in register with the addresses and successive bills have the same printed data and different addresses, said machine comprising revolvable data printing forms circumferentially spaced apart by distances corresponding to the address positions, addressing mechanism providing a fixed addressing position and having means for applying repetitions of the same address to any one bill form and different addresses to different bill forms when they are in the addressing position, the combination therewith of bill-form positioning means which positions different predetermined parts of any bill form in the same addressing position and each bill form in the same predetermined position with respect to a predetermined data printing form, said positioning means including bill-form advancing means and a plurality of bill-form positioning members spaced apart by distances corresponding to the spacing between said different predetermined parts of the bill form and also to the spacing between the printing forms and successively operable to halt the advance of the bill form while the addresses are being applied thereto, one of said positioning members being positioned in predetermined relation to a predetermined printing form at the start of the printing of any bill form so that each bill form is positioned to be engaged by that printing form at the same place and possibility of cumulative error is avoided.

26. A bill printing machine comprising addressing means for applying repetitions of the same address on any one bill and different addresses on different bills, printing means for printing the same data on all bills, and bill-form positioning means for positioning the same parts of all successive bill forms in the same positions in both the addressing and the printing means so that the addresses and printed data are in the same unchanging registration in all bill forms and possibility of cumulative error is avoided.

HARMON P. ELLIOTT.
